UNITED STATES PATENT OFFICE.

EDWARD HOTTER, OF CHICAGO, ILLINOIS.

CORE-PULLING DEVICE.

Application filed December 17, 1924. Serial No. 756,406.

To all whom it may concern:

Be it known that I, EDWARD HOTTER, a citizen of the United States, residing at Chicago, in the county of Cook and State of Illinois, have invented new and useful Improvements in Core-Pulling Devices, of which the following is a specification.

This invention relates to core pulling devices for die casting machines.

10 Heretofore, in most cases, cores have been pulled by hand. This is an expensive operation and requires that the dies be made larger than ordinarily required in order to support the rack and pinion pulling devices heretofore employed. In casting with aluminum or zinc base alloys and with tin alloys, the metal on cooling shrinks on the cores, making it exceedingly difficult to withdraw the cores from the castings, and unless 15 the cores are withdrawn at the proper time during the cooling operation it is impossible to remove the cores without melting the castings.

20 The main object of my invention is to provide a core puller so constructed as to exert more power in pulling the cores than the devices heretofore used and thus overcome sticking of the cores in the castings by shrinkage of the latter.

25 A further object of my invention is to provide a core puller enabling a plurality of cores to be pulled either simultaneously or independently.

30 Another object of my invention is to so construct the core puller that it may accommodate cores arranged at different angles to the die mold and in different offset positions, thus making the puller adaptable for universal work.

35 A further object of my invention is to provide a simple and efficient construction which may be used in connection with most any type of die-casting machine.

40 The invention consists further in the matter hereinafter described and claimed.

In the accompanying drawings:—

45 Figure 1 is a front view of a core puller constructed in accordance with my invention and showing the parts with the cores in the die mold;

50 Figures 2 and 3 are horizontal and vertical sectional views, respectively, taken on lines 2—2 and 3—3, of Fig. 1.

55 Figure 4 is a front view showing the cores withdrawn from the die mold;

Figure 5 is a view of the die mold to show the guiding means;

Figure 6 is a side view of the core puller;

Figure 7 is a top plan view thereof, the operating screw being shown in section; 60

Figure 8 is a view of one of the toggles to illustrate a detail of construction; and

Figure 9 is a perspective of the casting made by the die mold and cores shown in Figs. 1 and 2. 65

In the drawings 1, 1 indicate the two pairs of vertically spaced horizontal supporting rods employed in a die-casting machine and on which rods is a power-operated slide 2. The die mold construction is shown in Fig. 70 5 and as illustrated comprises two separable die members 3, 4. The die member 3 is carried by a box 5 on the slide 2. In this box works the pushoff plate 6 with its pins and is similar to the structure shown and described in my co-pending application Serial No. 751,779, filed November 24, 1924. 75

The other die member 4 is carried by a box 7 on plate 2^a which is held stationary in the machine. 80

As shown in Figs. 1 and 5, the box 5 is provided on the outside with two laterally projecting lugs 8, 8. These lugs are arranged on opposite sides of the box and at opposite corners as shown. Said lugs carry 85 guide pins 9, 9 and are adapted to enter holes 10, 10 in the lugs 8^a, 8^a in the other box 7 to guide the dies in the proper register when closing the die.

By having the guide pins 9, 9 outside of 90 the die, the latter may be made smaller than heretofore because it is not necessary to make the die large enough for the pins to pass through it, as heretofore employed. This also reduces the expense of the construction by reducing the amount of steel required for the die. Moreover, only two outside guide pins are required for each die construction instead of four inside pins as heretofore. 95

100 In the drawings, I have shown the die so made as to produce the type of casting shown in Fig. 9. This casting has a tubular body portion 11, and laterally projecting offset bosses 12, 12 on opposite sides thereof 105 with one boss adjacent one end of the casting and the other adjacent on the other end. For this type of casting three cores 13, 14, 14 are employed. The core 13 is for the body part 11 of the casting and the cores 14, 110

- 14 are for the side bosses 12. These cores as shown in Figs. 1 and 4 are arranged with the cores 14 at right angles to the core 13 and at opposite sides thereof.
- 15 The core 13 is carried by a slide 15, movable between guides 16, 16 mounted on the main slide 2 and adjustably secured thereto by bolts 17, 17. As shown in Figs. 6 and 7, the slide 15 is provided on its rear side with a boss 15^a to which is attached the lower end of a screw 18. This screw extends through a threaded boss 19 fixed to the main frame of the device so that on turning the hand-wheel 21 the slide 15 is moved to carry the core 13 into and out of the die. The hand-wheel 21 shown in Figs. 1 and 4 is provided with a plurality of pins 22, which may be grasped by the operator on turning the screw.
- 20 On opposite sides of the die are slides 23, 23 each connected with one of the cores 14 for moving these cores into and out of the die mold. For each slide 23 there is a lever 24 fulcrumed on one of the adjacent rods 1, 25 as shown in Figs. 1 and 4. The lower end of each lever 24 crosses its associated slide 23 and by a link 25 is connected with its slide. As shown in Fig. 6, the slide 23 by dovetail or equivalent means is connected 30 with a supporting member 26 carried by the main slide 2. The upper ends of the levers 24 are connected by toggle mechanisms with the slide 15 and guides 16, respectively. By this construction, the slides 23 may be moved 35 with the slide 15 on actuation of the screw 18 to move the cores 13 and 14 into and out of the die mold.
- The toggle mechanism for each lever 24 embraces three links 27, 28 and 29. These 40 links have pivotal connection at their meeting ends. The link 27 is pivoted to its lever 24, the link 28 to the slide 15, and the link 29 to the associated guide 16 through a plate 30. Links 27 and 28 extend through blocks 45 trunnioned on the lever 24 and slide 15, respectively, so that these links may pivot about these parts in the operation of the device. The links are on center and are thus locked against accidental movement 50 when the cores are in the die as shown in Fig. 1. On moving the slide 15 upward the links break and cause the levers 24 to withdraw the cores 14 from the die as shown in Fig. 4.
- 55 To regulate the movement of the cores and thus control the distance that the cores extend into the die, two collars 31, 32 are provided on the screw 18 on opposite sides of a boss 19 forming a part of the upright frame 20, which also includes the guides 16. This screw has two sets of threads, one on top of the other, with the main thread of a coarse pitch for moving the screw endwise. The fine pitch thread is for the 60 collars 31, 32. The collar 31 is split and has a clamp screw 33 for setting the collar on the screw. The collar 32 is slotted and carries a set-screw 34 for tightening the collar on the screw 18. After the cores have been brought to the proper position in the die the collar 31 is set on the screw 18 against the top of the boss 19 as shown in Fig. 6, and is then clamped to the screw. The device is then operated to completely withdraw the cores 13, 14 from the die and 70 the collar 32 is then set up against the underside of the boss 19 and clamped to the screw 18 so as to control the travel of the screw 18 for the particular die for which the parts have been set. By these means it 80 is possible to set the travel of the screw 18 for different lengths of cores.
- The links 27, 28 are threaded and pass loosely through their respective trunnion blocks 35 as shown. Each link is provided 85 with two sets of nuts 36, 36 on opposite sides of its block 35. When these nuts are brought against the blocks, the links are held against any endwise movement through the blocks in the actuation of the toggles. By adjusting the nuts on the links the travel of the cores 14, 14 may be accurately adjusted. By adjusting the nuts 36 away from the blocks 35 lost motion (Fig. 8) is provided in the 90 toggle action, thereby permitting the device 95 to withdraw any particular core or set of cores from the die independently of the action of the other core drawing parts. By this construction the device may be used with cores having different lengths and the 100 cores moved in timed relation so as to withdraw all of them from the die either dependently or independently.
- For the links 28 the blocks 35 are mounted between an outside plate 37 and bracket lugs 105 38 on the slide as shown in Figs. 6 and 7.
- As shown in Figs. 1, 4 and 6, a block 39 is connected by dovetail or equivalent connection in the bottom of the slide 15 so that this block may have adjustment toward 110 and from the main slide 2. A plurality of T slots 40 are provided in the underside of the block 39 and these slots extend across the block transverse to its adjustment with the slide 15. Fixed to the upper side of the 115 die box 5 there is a bracket 41 through which the core 13 operates and has its upper end headed and received in one of the cross slots 40. The bracket 41 extends outward over the die member 3 so that the core 13 may 120 enter the die. By having a plurality of cross slots 40 the core 13 may be used with dies of different depths. The block 39 is not clamped to the slide nor is the core 13 clamped to the block, thus allowing the core 125 to center itself with respect to the cavity in the die so that the core will be withdrawn straight out of the die without binding against the casting, to crack it as frequently happens in devices as heretofore used.

The lower end of each lever 24 is provided with an elongated slot 42 as shown in Fig. 6. The outer end of the link 25 extends through this slot and is pivotally connected with lugs or ears 43 on a plate 44 clamped by bolts 45 to the lever 24 at the slot. The plate 44 is also slotted for the outer end of the link to extend through, as shown in the drawings. The bolts 45 extend inward into the slot 42 and have the heads at their inner ends in grooves 46 in the lever 24, as shown in the drawings.

As shown in Figs. 2 and 3 the inner end of each link 25 engages about a bushing 47 on the associated bolt 48 carried by the slide 23. The inner end of the bushing engages teeth formed in the slide 23 as shown, there being a clamp nut on the screw to hold the bushing from slipping on the slide. This slide 23 is provided with a T slot 49 to receive the headed inner end of the bolt 48, so that adjustment of the parts may be made when required.

As shown in Fig. 2, the slide 23 is L-shaped and arranged with the right-angled part 50 extending outward from the main slide 2. A block 51 has a dovetail or equivalent connection with the part 50 so as to have adjustment to and from the main slide 2. This block is provided on its front side with a plurality of cross grooves 51^a adapted to receive the headed end of the associated core 14, by means of which the core is connected with the slide for moving the core into and out of the die. The core 14 moves through a bracket lug 52 on the box 5 in the same manner as the structure described for the core 13. With the core 14 adjustably connected with its slide without clamping means permits centering of the core in the die in its operation the same as the core 13.

To regulate the leverage of the device as may be required with different sizes of cores, each lever 24 is provided with a pair of upwardly extending bars 53 adjustably secured to the lever, on opposite sides thereof, by bolts 54 as shown in Figs. 1 and 2. These bars extend beyond the upper ends of the levers and by adjusting them up and down the leverage of the device may be regulated.

To accommodate this change in leverage the plates 30 by bolts 55 having their heads in T slots 56 in the guides 16, 16 may raise and lower the centers about which the links 29 move in the operation of the device. The angle plates 26, 26 are secured to the sides of the main slide 21, bolts 57, 57 having their heads in T slots 58, 58 in the slide 2 for vertical adjustment.

While I have shown and described herein in detail a core pulling device of my invention, it is of course to be understood that the details of construction and arrangement of parts may be variously changed and

modified without departing from the spirit and scope of the same.

I claim as my invention:

1. In a die-casting machine, the combination with a die mold having cores arranged about the same, of a core pulling device having means for moving said cores either simultaneously or independently into and out of the die mold, and means for adjusting the extent of travel of the cores into the die mold. 70

2. In a die-casting machine, the combination with a die mold having cores arranged about the same, of a core pulling device having means for moving the cores either simultaneously or independently into and out of the die mold, and means for varying the power exerted by said device. 80

3. In a die-casting machine, the combination with a die mold, of a core pulling device on said machine and having a plurality of cores arranged about the die mold, and means including a toggle mechanism and a screw for moving the cores into and out of the die mold on the actuation of said screw. 85

4. In a die-casting machine, the combination with a die mold, of a core pulling device on said machine and having levers for operating cores on opposite sides of the die mold, a toggle mechanism and an actuating screw for moving the levers to carry the cores into and out of the die mold, said levers being adjustable for varying the leverage exerted thereby on the cores. 95

5. In a die-casting machine, the combination with a die mold, of a core pulling device on said machine and having levers for operating cores on opposite sides of the die mold, a toggle mechanism connected with said levers for moving the cores into and out of the die mold, means for providing lost motion in the action of the toggles for regulating the travel of the cores, and means for actuating the toggles. 100

6. In a die-casting machine, the combination with a pair of stationary rods, of a die mold there-between, a core pulling device having a pair of levers fulcrumed on said rods and operating cores on opposite sides of the die mold, and a toggle mechanism for actuating the levers for moving the cores into and out of the die mold. 110

7. In a die-casting machine, the combination with a die mold, of a pair of levers fulcrumed on the machine on opposite sides of the die mold for moving cores into and out of the die mold, and a toggle mechanism for actuating said levers, said mechanism being adjustable for regulating the locking action of the toggles. 115

8. In a die-casting machine, the combination with a die mold, of a main slide, a pair of levers fulcrumed on the machine on opposite sides of the die mold for moving the cores into and out of the same, and toggle 120

- mechanism for actuating said levers and having screw-threaded links extending loosely through blocks trunnioned on the levers and slide, respectively, clamp nuts on said links for providing lost motion in the toggle action.
9. In a die-casting machine, the combination with a die mold, of a core pulling device including a lever fulcrumed on the machine and having one end at one side of the die mold, and means interposed between the lever and the die mold for converting the arcuate movement of the lever into a straight line movement for moving the core into and out of the die mold.
10. In a die-casting machine, the combination with a die mold, of a core pulling device including a lever fulcrumed on the machine and having one end at one side of the die mold, a slide between the lever and the die mold and engaged with a core, and a link connecting the lever to the slide for moving the core into and out of the die mold in the actuation of the lever.
11. In a die-casting machine, the combination with a die mold, of a core pulling device including a lever fulcrumed on the machine and having one end at one side of the die mold, a slide between the die mold and lever and connected with a core, and a link connecting the slide to the lever for moving the core into and out of the die mold, said link having an adjustable connection with the slide.
12. In a die-casting machine, the combination with a die mold, of a core pulling device including a lever fulcrumed on the machine and having an end at one side of the die mold, a slide between the lever and the die mold and connecting with a core, and a link connecting the slide to the lever for moving the core into and out of the die mold, said slide having an elongated slot to receive a bolt carried by the link with a serial connection between the slide and the bolt for adjusting the travel of the core.
13. In a die-casting machine, the combination with a die-mold, of a carrying member therefor, a core pulling device associated therewith and having core operating slides operable in the same plane and arranged above and on opposite sides of the die-mold, and means for moving the slides either simultaneously or independently for moving the cores into and out of the die mold.
14. In a die-casting machine, the combination with a core and the die carrying member, of a core pulling device including a slide carried by said member, and a block carrying said core and adjustably mounted on said slide to adjust the position of the core.
15. In a die-casting machine, the combination with the die carrying member, of a core pulling device including a plurality of slides arranged two on opposite sides of the die and one above the same, levers fulcrumed on the machine and connected with the slides on opposite sides of the die, a screw connected with the slide above the die for moving the same, a toggle mechanism operated by said screw and connected with said levers for operating the same.
16. In a die-casting machine, the combination with the die mold construction having a core guide, of a core pulling device including a slide for the core and a block carried by said slide and having a groove to receive the outer end of the core so that the core may have a centering action on moving into the die mold through the guide.
17. In a die-casting machine, the combination with the die carrying member, of a core pulling device including a frame on said member, a slide in said frame and carrying a core for the die, a screw having a shallow thread and a deep thread with the deep thread engaged with the boss on the frame and connected with the slide for actuating the same, adjusting members engaging the shallow thread of the screw and on opposite sides of the boss for adjusting the travel of the screw.
18. In a die-casting machine, the combination with the die carrying member, of a core pulling device at said member and having a lever fulcrumed on said machine for moving a core into and out of the die, a toggle mechanism connected with said lever for moving the same, said lever being adjustable to vary the leverage thereof and said toggle mechanism having adjustable connection with a fixed part of the device for adjusting the toggle action to accommodate for the adjustment given to the lever.
19. In a die-casting machine, the combination with a die carrying member, of a core pulling device including slides on said member and arranged about the die mold with cores connected with said slides, a toggle mechanism and a screw for operating said slides, and a hand wheel with grab pins connected with said screw whereby the same may be turned.
20. In a die-casting machine, the combination with a die mold, of a core pulling device on the machine at said mold and including a lever fulcrumed on the machine, a slide between the mold and lever and connected with a core, a link between the slide and lever, said link having its ends pivoted to the slides and lever, respectively, and having adjustable connection with said respective parts, and means for actuating said lever.
- In testimony that I claim the foregoing as my invention, I affix my signature, this 12th day of December, 1924.

EDWARD HOTTER.
